Term of patent 14 years

Int. Cl. D9—01

U.S. Cl. D9—141

FIG. 1

FIG. 2

FIG. 1 is a side elevational view of a combined jar and lid showing my new design, and

FIG. 2 is a top plan view thereof.

This application is a continuation-in-part of my earlier, copending application Ser. No. 21,051 filed Jan. 23, 1970 and now abandoned.

I claim:

The ornamental design for a combined jar and lid, substantially as shown and described.
